UNITED STATES PATENT OFFICE.

FLOYD H. BRANDENBURG, OF KLAMATH FALLS, OREGON.

TOILET-SEAT.

1,196,427.

Specification of Letters Patent. Patented Aug. 29, 1916.

Application filed June 29, 1915. Serial No. 37,023.

To all whom it may concern:

Be it known that I, FLOYD H. BRANDENBURG, a citizen of the United States, residing at Klamath Falls, in the county of 5 Klamath and State of Oregon, have invented certain new and useful Improvements in Toilet-Seats; and I do hereby declare the following to be a full, clear, and exact description of the invention, such as will enable others skilled in the art to which it 10 pertains to make and use the same.

This invention relates to improvements in toilet seats and especially with reference to the provision of a smaller seat for use by 15 children, and which is hingedly connected to the seat and to the lid and is adapted to be arranged in and carried by the lid, so as to be out of the way when not in use, and is also adapted to be readily arranged in the 20 seat, when desired, the object of the invention being to provide an improved device of this character which is simple, in construction, is strong and durable, and is not likely to get out of order.

25 The invention consists in the construction, combination and arrangement of devices hereinafter described and claimed.

In the accompanying drawings:—Figure 1 is a front elevation of a toilet seat constructed in accordance with my invention and with the lid and smaller seat raised. Fig. 2 is a plan of the same, with the smaller seat lowered and the lid raised and shown in perspective form above. Fig. 3 is a plan of 35 the same with the lid closed. Fig. 4 is a vertical transverse sectional view of the same with the lid raised and the smaller seat in place in the seat. Fig. 5 is a vertical longitudinal sectional view of the same. 40 Fig. 6 is a detail perspective view of the smaller seat.

The seat 1 and lid 2 may be of any suitable size and shape and made of any suitable material and are hingedly connected to 45 a fixed member 3 so that they may be raised and lowered. A hinged plate 4 is shown on the fixed member 3, a hinged plate 5 is shown on the rear portion of the seat and the lid is shown as provided with hinge 50 plates 6. These hinge plates are engaged by a common pintle rod 7. Any suitable pivotal or hinge connection may, in accordance with my invention, be employed for connecting the seat and lid with the fixed member. I also, in accordance with my invention provide a small seat 8, which may

be made of any suitable material and is adapted to be lowered and fitted in the seat 1. This smaller seat is here shown as provided on its lower side with a reinforcing 60 plate 9, made of suitable sheet metal but this reinforcing plate may be omitted if desired. The reinforcing plate is here shown as provided with a hinge arm 10, which coacts with the hinge plates 4—5—6 and is also 65 pivotally mounted on the common pintle 7 so that the lid, the seat, and the smaller seat have a common pivotal axis. The lid is provided on its front side with a recess 11 which corresponds in size and shape with the 70 smaller seat and its hinge arm 10 and adapts the smaller seat to be raised and arranged in the said recess so as to be entirely out of the way. A spring latch 12 is provided which is secured as shown at 13 at the lower 75 side of the recess 11 and the shoulder head 14 of which is adapted to pass through an opening 15 in the small seat and to engage at the side of said opening and thereby lock the small seat to the lid when the small 80 seat is raised and arranged in the recess 11. By disengaging the latch from the small seat the latter may be readily lowered from the lid and to facilitate the disengagement of the small seat the lid is here shown as 85 provided with a finger slip 16 under the upper side of the recess 11.

The parts of the improved seat may be made of any suitable material and any suitable means may, within the scope of the invention, be employed for hingedly connecting the seat, the lid and the smaller seat to the fixed member and for independent pivotal movement.

While I have herein shown and described 95 a preferred form of my invention, I would have it understood that changes may be made in the form, proportion and construction of the several parts without departing from the spirit of the invention and within 100 the scope of the appended claim.

Having thus described my invention, I claim:—

A device of the class described comprising 105 a fixed member, a toilet seat hingedly connected to the fixed member, a cover hingedly connected to the pintle of the hinge between the seat and fixed member, a frame comprising an elliptical body, an arm formed on said body, said arm being hingedly connected to the said pintle, a smaller seat fitted in said frame, said cover provided on its 110

inner face with an elliptical groove terminating at its lower end into a recess which extends through the hinge end of said cover, a catch arranged in said groove, said frame and smaller seat adapted to be fitted into said groove and held securely therein when not in use substantially as described.

In testimony whereof I affix my signature in presence of two witnesses.

FLOYD H. BRANDENBURG.
